UNITED STATES PATENT OFFICE.

FREDRICK A. LEWIS, OF LOS ANGELES, CALIFORNIA.

HAND-TOOL.

1,324,258.

Specification of Letters Patent.

Patented Dec. 9, 1919.

Application filed March 24, 1919. Serial No. 284,765.

To all whom it may concern:

Be it known that I, FREDRICK A. LEWIS, a citizen of the United States, and a resident of Los Angeles, in the county of Los Angeles, State of California, have invented certain new and useful Improvements in Hand-Tools, of which the following is a specification.

My invention relates primarily to a hand tool known as the ratchet type usually supplied with a multiplicity of different types of tools for use therewith, which tools are adapted to be detachably mounted in the head of the tool when positioned for use, and the prime object thereof is to provide a tool of the character above described having an adjustable head whereby the device may be used in close quarters, such as in corners, against partitions and the like, or it 20 may be used in the ordinary manner.

Other objects and advantages will appear hereinafter and while I have shown and will describe my preferred form of my invention it will be understood that I do not 25 limit myself to such preferred form but that various changes and adaptations may be made therein without departing from the spirit of my invention.

In the drawings accompanying and forming 30 a part of this application:

Figure 1 is a longitudinal section, partly in elevation, of my invention.

Fig. 2 is a sectional elevation of a portion of Fig. 1, at a right angle thereto.

Fig. 3 is an elevation of Fig. 2.

Fig. 4 is a section on the line 4—4 of Fig. 2.

Fig. 5 is a perspective view of a portion of my device.

Fig. 6 is a side elevation of the lower portion of Fig. 1.

Fig. 7 is a front elevation of the lower portion of Fig. 1, showing the same in its adjustable position.

Fig. 8 is an enlarged sectional detail of a portion of my device.

Referring to the drawings my device comprises a cylindrical body member 10 on the upper end of which is revolubly mounted a handle member 11 closed at its upper end by a detachable cap 12.

Extending longitudinally of members 10 and 11 is a spindle 13 revolubly mounted at its upper end in a bearing 14 mounted in 55 the upper end of handle member 11, which bearing is provided with a downwardly ex-

tending hub 15. Revolubly mounted upon the upper end of member 10 within handle 11 is a tube member 16 the upper end of which is rigidly secured to hub 15 of bearing member 14. A collar 17 rigidly connected to tube 16 rests upon the upper end of member 10 and serves to hold said tube in position. Rigidly mounted upon spindle 13 within tube 16 are ratchet wheels 18 and 19 which are mounted opposed to each other, that is, right and left, and mounted in the outer wall of tube 16 are opposed pawls 20 and 21 adapted for engagement with said ratchets. These pawls are substantially L-shaped in top plan and are mounted in openings 22 and 23 cut in tube 16. Extending outwardly from the outer wall of tube 16 at each side of openings 22 and 23 are retaining strips 24 and 25 which serve to confine 75 pawls 20 and 21 within said openings. Slidably mounted upon the outer side of tube 16 between strips 24 and 25 to slide longitudinally is a pawl operating member 26 provided on its outer face with a projecting 80 knob 27, which knob projects through a rectangular opening 28 in handle member 11. Secured to the underside of member 26 centrally thereof is a flexible pawl depressing member 29 of a length and configuration to 85 hold one pawl depressed and the other elevated alternately, so that when member 26 is moved in one direction one pawl will be locked in engagement with its ratchet while the other will be locked out of engagement 90 with its ratchet and vice versa. Rigidly mounted upon the lower end of member 10 is a yoke 30 the arms of which extend downwardly and in the free ends of said yoke are pivotally mounted the free ends of an up- 95 wardly extending yoke 31.

Extending transversely through the contacting arms of yokes 30 and 31 is a pintle bolt 32, one end of which is rigidly secured in one of the arms of yoke 30 by means of 100 pin 33 and the other end terminates in a T-shaped head 34 a short distance beyond the outer face of the other arm of yoke 30 for a purpose hereafter explained. Loosely mounted upon bolt 32 between the arms of 105 said yokes is a sleeve 32^a upon which are revolubly mounted opposed bevel gears 35 and 36 which gears mesh with gears 37 and 38, gear 37 being rigidly mounted upon the lower end of spindle 13 and gear 38 being 110 revolubly mounted in the body portion of yoke 31. A tapered rectangular socket is

provided in the hub 39 of gear 38 for the reception of a screw driver 40 or like tool. Revolubly mounted upon pintle bolt 32 between head 34 and the hub of gear 36 is an 5 adjusting member 41 the outer end of which terminates in opposed cam faces 42 and 43 adapted to engage the under side of head 34 when rotated and be caused to slide along bolt 32. Coiled around sleeve 32^a between 10 the opposed faces of gears 35 and 36 is a coil spring 44 which acts to normally force gear 36 out of engagement with gears 37 and 38. Extending upwardly from the end of member 41 is an operating arm 45 in the 15 free end of which is pivotally mounted a stop 46 adapted to engage teeth 47 in yoke 30 and lock said arm against movement.

In the operation of my device the head is first adjusted to extend in the desired direction in the following manner:

Dog 46 is operated to release arm 45 which is then moved to rotate adjusting member 41 thereby permitting spring 44 to force gear 36 out of engagement with 20 gears 37 and 38 when the lower yoke may be moved to extend in the desired position. The arm 45 is then rotated to its normal position when the yoke is again locked against movement. The pawl operating member is 25 then moved to the position necessary to rotate the spindle in the desired direction and the device is ready for use.

Having described my invention what I claim is:

35 1. In a hand tool a head therefor comprising a pair of opposed yokes having their free ends pivotally mounted together; a pair of opposed bevel gears loosely mounted on said pivot between the arms of said yokes; 40 a spring coiled around said pivot between the opposed faces of said gears; and a cam

member rotatively mounted on said pivot between the outer face of one of said gears and the head of said pivot whereby when the same is rotated said gears will be moved 45 toward each other; a bevel gear revolubly mounted in the lowermost one of said yokes in mesh with said first mentioned gears; and a bevel gear mounted on the lower end of the hand tool spindle in mesh with said first 50 mentioned gears whereby when said spindle is rotated all of said gears will be caused to rotate.

2. A head for hand tools comprising a pair of oppositely positioned yokes pivotally connected together at their free ends; one of said yokes being rigidly connected intermediate its arms to the body portion of the hand tool; a pintle bolt connecting the free ends of said yokes having a head; a 60 sleeve loosely mounted on said pintle bolt; a pair of opposed bevel gears loosely mounted on said sleeve; a spring coiled around said sleeve between said gears adapted to force the same apart; a cam member revolubly mounted on said pintle bolt between one of said gears and said head adapted when rotated to force said gears toward each other against said spring; means to lock said cam member in any desired position; a 65 bevel gear normally meshing with both of said first mentioned bevel gears rigidly mounted upon the spindle of the hand tool; a bevel gear rotatively mounted in the other one of said yokes intermediate its arms normally meshing with both said first mentioned gears; and a tool detachably mounted in said last gear.

In witness that I claim the foregoing I have hereunto subscribed my name this 15th 70 day of March, 1919.

FREDRICK A. LEWIS.
